SLEEVE PUFFING APPARATUS

James E. Heilman and Roy D. Brooks, Henderson, Tex., assignors of one-third to J. A. Rouetree, Henderson, Tex.

Application February 5, 1953, Serial No. 335,362

4 Claims. (Cl. 223—73)

This invention relates to a device for finishing the sleeves and other tubular portions of fabric garments.

In the finishing of the sleeves or other fabric garments, it is desirable to minimize the handling of the garments both to accelerate the finishing process and also to prevent wrinkling of previously finished portions of the garment. It is desirable, therefore, to provide a device for finishing such tubular portions of garments which is easily portable so that the operator may move along a finishing line on which a plurality of garments are hung on the usual hangers and finish the sleeves and other tubular portions of the garments without removing the garments from the hangers.

Accordingly, it is an object of the invention to provide a new and improved device for finishing tubular portions of fabric garments.

It is another object of the invention to provide a new and improved portable device, of the type described, which may be carried from one garment to the next and inserted in the tubular portions thereof.

It is a further object of the invention to provide a device of the type described which is supplied with steam through a flexible hose or conduit.

A still further object of the invention is to provide a finishing device for tubular portions of garments which is light in weight and of simple durable construction.

With the foregoing objects in view, the invention has further reference to certain features of accomplishment which will become apparent as the description proceeds, taken in connection with the accompanying drawing wherein:

Figure 1 is a side elevation of a preferred form of the device with some portions broken away, for finishing tubular portions of fabric garments;

Figure 2 is a vertical sectional view taken on the line 2—2 of Figure 1;

Figure 3 is a side elevation, with parts broken away, of another form of the device shown in Figures 1 and 2;

Figure 4 is a vertical sectional view taken on the line 4—4 of Figure 3; and

Figure 5 is a vertical sectional view taken on the line 5—5 of Figure 3.

Referring now especially to Figures 1 and 2 of the drawing, the device 10 for refinishing sleeves and other tubular portions of fabric garments includes a substantially U-shaped rigid pipe 11 or conduit having parallel straight portions 12 and 13, and a bight 14. The ends of the conduit remote from the bight 14 are converged and are secured to a hollow fitting or coupling 15. The straight portions 12 and 13 and the bight 14 are provided with a plurality of perforations 16 through which steam may pass.

An elongate pad cover 17 made of steam permeable material extends about and covers the perforate pipe and is in turn covered by a steam bag 18. The open end portions of the pad cover and steam bag are disposed adjacent the coupling 15 and are firmly secured thereto by any suitable screw clamp 19. The clamp is

2

disposed between the convergent end portions of the perforate conduit 11 and the outwardly extending flange 20 integral with the coupling 15 so that the open ends of the pad cover and the steam bag are held against longitudinal displacement of the coupling 15.

The pad cover and the steam bag are shown in expanded positions but it will be realized that these elements are normally collapsed on the perforate conduit and are expanded only when steam is admitted to the perforate conduit through the coupling 15.

The coupling 15 is connected to, as by threads, the outlet 21 of a steam gun or valve 22 having a pistol grip 23 and an actuating lever 24. A flexible hose or conduit 25 has opposite ends firmly connected to the inlet 26 of the steam gun or valve 22 and the outlet 27 of a valve 28 on the steam tank 29 which controls the flow of steam from the steam tank into the flexible conduit. The flexible conduit 25 may be secured to the steam gun or valve 22 and the valve 28 by means of screw clamps 30.

The steam tank is provided with an inlet 31 controlled by a valve 32 and an outlet 33 having a steam trap 34. A faucet or bleed cock 35 is provided adjacent the bottom of the tank to permit condensed water to be drained from the interior of the tank.

In use, the valve 32 is opened to permit steam to enter the steam tank 29 through the inlet 31 from any suitable source of steam, such as a boiler. The outlet 33 and steam trap 34 which are disposed substantially below the inlet, permit the cooler, more moist steam which settles to the lower portions of the tank to escape so that a continuous supply of relatively hot dry steam continuously flows into the tank. The valve 28 is then opened and permits the hot dry steam in the upper part of the tank to pass into the flexible conduit to the steam gun or valve 22.

The operator holds the steam gun in one hand by its pistol handle 23 and seizes the sleeve of a garment hung on a hanger on a finishing line. The operator then inserts the perforated conduit 11 into the sleeve and squeezes the operating lever 24 of the steam gun so that steam is admitted to the perforated conduit from the steam tank or chamber 29. The steam issuing from the perforations 16 in the conduit 11 expands the pad cover 17 and passes through it to expand the steam bag 18. The sleeve is thus expanded by the steam bag and at the same time is treated with steam which penetrates outwardly through the steam bag. The operator then releases the actuating lever 24, the steam bag and the pad cover collapse back on the perforated conduit and the perforated conduit is easily withdrawn from the sleeve. The operator can then pass along to the other sleeve of the garment and subject it to the same treatment or he may treat a sleeve of the next garment hanging on the finishing line. The light weight of the perforated conduit and the pad cover and steam bag enable the operator to easily handle the device. The flexible hose or conduit 25 enables the operator to move along the finishing line and treat the garments without taking them off the finishing line.

The hose 25 may be provided with a hanger having one or more hooks 36 by means of which it can be supported on fixed structures so that the operator does not have to drag the hose on the ground or support its full weight.

It will be seen now that a new and improved device for treating tubular portions of garments has been described which includes a pad cover 17 and a steam bag 18 which are expansible by steam issuing from the apertures 16 in the perforated conduit 11 to expand sleeves and the like to remove wrinkles therein and at the same time treat the sleeves with steam. It will also be seen that the device is readily portable so that the garments do not have to be handled or brought to the device.

In Figures 3 to 5 is shown a modified form of the finish-

ing device wherein the steam gun or valve 22 is employed to transmit steam to a T-coupling 37. A slightly arcuate conduit 38 is connected to one outlet 39 of the T-coupling while a second conduit 40 is connected to the other outlet 41 of the T-coupling through a flexible hose or conduit 42. Each of the conduits has a plurality of perforations 43 through which steam may escape from the interiors of the perforated conduits.

The conduit 38 has two pairs of lugs 44 to each pair of which one end of a link 45 is pivotally connected, as by bolts 46. The conduit 40 is similarly provided with two pairs of lugs 47 to each pair of which one end of a link 48 is pivotally connected, as by bolts 49.

The front links 45 and 48 are pivotally connected by means of a bolt 50 which also rotatably supports a pulley 51. The back links 45 and 48 are pivotally connected by means of a bolt 52. One end of a line or cable 53 is connected to the bolt 52 and passes around the pulley 51 and through a guide loop 54 to the operating lever 24 of the steam gun, the other end of the line or cable 53 being secured to the operating lever 24.

It will be seen that when the operating lever is squeezed, the line serves to draw the bolts 46 and 52 toward one another causing the links to pivot about their ends to cause the conduits 38 and 40 to move apart. Each pair of links 46 and 48 is connected by a spring 55 which biases each pair of links 46 and 48 toward one another so that when the operating lever 24 is released, the perforated conduits 38 and 40 will move toward one another.

Each of the perforated conduits is covered by a pad cover 56 and a steam bag 57 which are secured thereon by screw clamps 58. The pad covers and steam bags are provided, of course, with suitable apertures through which the lugs 44 or 47 extend.

The form of the finishing device illustrated in Figures 3 to 5 is especially adapted for use on tubular portions of heavy garments such as overcoats. It will be apparent that when the perforated conduits are in the retracted positions shown in Figure 3, they are easily inserted in the sleeve of a coat or other garment. When the operating lever 24 of the steam gun 22 is squeezed, the line 53 is pulled and the perforated conduits are moved away from one another into expanded position against the interior surfaces of the sleeve. At the same time, the steam gun admits steam into the perforated conduits which expands the cover pads and steam bags. The sleeve is thus smoothed of wrinkles and is simultaneously treated with steam. When the operating lever 24 is released, the springs 55 draw the perforated conduits toward each other into retracted positions and at the same time the flow of steam into the perforated conduits is stopped. The device can then be easily withdrawn from the sleeve.

Manifestly, the construction as shown and described is capable of some modification and such modification as may be construed to fall within the scope and meaning of the appended claims is also considered to be within the spirit and intent of the invention.

What is claimed is:

1. A portable device for finishing tubular portions of garments comprising a pair of substantially parallel elongate conduits; spaced apart pairs of relatively pivoted links connecting said conduits for movement toward and away from one another; means connected between the links of each pair for biasing said conduits toward one another; a steam bag embracing each of said conduits, said conduits each having a plurality of perforations whereby said steam bags are expandable by steam escaping through said perforations; a steam valve connected to said conduits for admitting steam to said conduits having an operating lever; and means connected to said operat-

ing lever and to said connecting means whereby said perforated conduits are moved away from each other when steam is admitted thereto by said steam valve; said steam bags being expandable by steam flowing from said conduit through said perforations.

2. A portable device for finishing tubular portions of garments comprising a pair of actuated and substantially parallel elongate conduits; longitudinally spaced pairs of pivoted links connecting said conduits for movement toward and away from one another; means connected between the links of said pairs for biasing said conduits toward one another; a steam bag on each of said conduits, said conduits each having a plurality of perforations whereby said steam bags are expandable by steam escaping through said perforations; a steam valve connected to said conduits for admitting steam to said conduits and having an operating lever; a flexible line connected at one end to said operating lever and to the pivotal points of the links of each pair to effect movement of said perforated conduits away from each other when steam is admitted thereto by said steam valve; said steam bags being expandable by steam flowing from said conduit through said perforations.

3. A portable device for finishing tubular portions of garments comprising a pair of substantially parallel elongate conduits; a plurality of pairs of links connecting said conduits for movement toward and away from one another the links of each pair having adjacent ends pivoted together and their opposite ends pivoted to respective conduits; means connected between the links of each pair for biasing said conduits toward one another; a steam bag on each of said conduits; a pad cover interposed between each perforated conduit and its steam bag, said conduits each having a plurality of perforations whereby said steam bags are expandable by steam escaping through said perforations; a steam valve connected to said conduits and for admitting steam to said conduits having an operating lever; and flexible means connected to said operating lever and to said pairs of links whereby said perforated conduits are moved away from each other when steam is admitted thereto by said steam valve; said steam bags being expandable by steam flowing from said conduit through said perforations.

4. A portable device for finishing tubular portions of garments comprising a pair of curved elongate conduits; in substantial parallelism, pivoted links connecting said conduits for movement toward and away from one another; spring means connected to said links for biasing said conduits toward one another; a steam bag on each of said conduits; a pad cover interposed between each perforated conduit and its steam bag; said conduits each having a plurality of perforations whereby said steam bags are expandable by steam escaping through said perforations; a steam valve connected to said conduits for admitting steam to said conduits having an operating lever; and flexible means connected between said operating lever and said links whereby said perforated conduits are moved away from each other when steam is admitted thereto by said steam valve; said steam bag being expandable by steam flowing from said conduit through said perforations.
